United States Patent Office

Des. 210,900
Patented Apr. 30, 1968

210,900

PLATE

Sara L. Balbach, Corning, N.Y., assignor to Corning
Glass Works, Corning, N.Y., a corporation of New York

Filed Oct. 3, 1967, Ser. No. 8,839

Term of patent 14 years

(Cl. D44—15)

The figure is an enlarged scale fragmentary top plan view of a plate of conventional configuration showing my new design, with a repeat unit being shown between dotted lines.

I claim:

The ornamental design for a plate, as shown and described.
